UNITED STATES PATENT OFFICE.

ISAAC LEVIN, OF BROOKLYN, NEW YORK.

SECTIONAL GARMENT-FORM.

1,153,633.

Specification of Letters Patent. Patented Sept. 14, 1915.

Application filed May 16, 1914. Serial No. 838,936.

To all whom it may concern:

Be it known that I, ISAAC LEVIN, a citizen of the United States of America, residing at Brooklyn, Kings county, and State of New York, have invented certain new and useful Improvements in Sectional Garment-Forms, of which the following is a full, clear, and exact description.

This invention relates to improvements 10 in adjustable garment-forms, the particular object being to provide a sectional garment-form that can be adjusted at the neck, waist and hip portions as well as longitudinally to increase the length of the waist.

15 My improved form is made up of a plurality of sections, preferably rigid, consisting of hip, bust and shoulder portions, each of said portions being divided into sub-sections which are adjustably connected together. The hip, bust and shoulder sections as a whole are connected to a supporting post which consists of a plurality of independently operable members, one of said members being connected to the hip portions 25 and another to the neck-sections in a manner to render the portions connected thereto adjustable inwardly or outwardly. To increase the length of the waist I employ a novel method of rotating the supporting member to which the hip portions of the form are connected. By virtue of the fact that each portion of the form is made up of adjustably connected sections I am able 30 to alter the contour of the form independently of the adjustable support for the form.

Another advantageous feature of my invention is the provision of simple means for adjusting the contour or shape of the bust or breast portions of the form, besides which 40 I have provided special auxiliary adjustments of the hip portions of the form.

Further features of improvements will hereinafter appear.

I will now proceed to describe my invention in detail, the novel features of which I will point out in the appended claims, reference being had to the accompanying drawings, forming part hereof, wherein:

Figure 1 is a front view of a garment-form embodying my improvements; Fig. 2 is a rear view thereof, the support and skirt portion being omitted; Fig. 3 is a side view of Fig. 2; Fig. 4 is a side view of one half of the form; Fig. 5 is an enlarged interior view, looking from the rear, of one-

quarter of the form; Fig. 6 is an enlarged sectional plan view, the section being taken on a line 6-6 in Fig. 4; Fig. 7 is a sectional view, the section being taken on a line 7-7 in Fig. 6; Fig. 8 is an enlarged fragmentary side elevation of one of the supporting post-members; Fig. 9 is a side view, partly in section, showing the manner of connecting the elements which make up the supporting post member shown in Fig. 65 8; Fig. 10 is a sectional plan view, the section being taken on a line 10-10 in Fig. 8; Fig. 11 is an enlarged sectional view of the main portion of the supporting-post; Fig. 12 is a detail view showing the swivel connection for the supporting post; Fig. 13 is a sectional view, the section being taken on a line 13-13 in Fig. 11; Fig. 14 is a sectional detail view of the swivel connection, the section being taken on a line 14-14 in 75 Fig. 15; Fig. 15 is a sectional plan view, the section being taken on a line 15-15 in Fig. 12; and Fig. 16 is a sectional plan view, the section being taken on a line 16-16 in Fig. 11.

As herein embodied, my improved garment-form consists of a bust portion A, a hip portion B, and a skirt portion C, all of which are carried by a supporting post D mounted on a stand E. Referring to Fig. 85 11, the supporting post E consists of a plurality of rotatably connected members, namely, a primary tubular member 1, which rotatably supports a secondary threaded tubular member 2, and a threaded sleeve 3 90 carried by the secondary tubular member 2. The above members, taken in connection with a tubular member 4 slidable within the same, and a rod 5 (Fig. 4) slidable within the member 4, constitute the supporting post 95 for the form. The stand E carries the rod 5. To rotate the sleeve 3, I provide the same at the upper end, with a wing-nut 6. To rotate the secondary tubular member 2, I provide the same, at the upper end, with a hand-wheel 7.

To prevent longitudinal movement of the sleeve 3 on the member 2, I provide the member 2 with a thrust collar 8 upon which the sleeve 3 rests, the upper end of the sleeve 3 being secured in the wing-nut 6, as shown. The function of the member 2 is, when rotated, to alter the length of the waist of the form, and for this reason I provide the upper end of the post member 1 with a nut 105 110

9 engaging the threads of the member 2. The function of the post member 3 is, when rotated, to adjust the neck dimensions of the form and for this reason I provide the 5 said member with a right-hand thread 10 and a left-hand thread 11 and each threaded portion with a nut 12 and 13, respectively, each nut being connected by links 14 (Fig. 4.) to the neck section plates 15. The function 10 of the post member 1 is to adjust the hip dimension of the form. To this end I provide the member 1 with a right-hand thread 16 and a left-hand thread 17, Fig. 8, and said threaded portions with nuts 18 and 19, respectively. The nuts 18 and 19 are 15 connected by links 20 to special brackets 21 at the hip region of the form (Figs. 4, 6 and 7). To rotatably connect the upper and lower portions of the supporting post, in 20 order that the form can be rotated without turning the stand E, I provide the lower end of the member 1 with a flanged collar 22 (Figs. 12, 14 and 15) rotatably secured to a plate 23 carried by the post member 4, a 25 set-screw 24 being employed to secure the plate 23 to the post member 4. The plate 23 carries nibs 26 which engage the plate 22 in such manner as to prevent the flange and member 1 secured thereto from being withdrawn from the plate 23, but not to prevent the rotation thereof on said plate. The 30 form can be held against rotation at any time by tightening the thumb-screw 27, which prevents the flange 22 from rotating. 35 One of the features of my invention is the means for rotating the post member 1 in order that the hip-portions of the form can be adjusted. To rotate the member 1, I 40 employ a rod 28 (in this instance square) which passes loosely through the secondary post member 2 and engages a plug 29 having a square opening 30 in said plug. To prevent longitudinal movement of the rod 28 I 45 employ a thrust-collar 31 abutting against the lower end of the secondary post member 2. The nut 9 and plug 29 are held in place by annular ribs 32 and 33 carried by the post member 1. The upper end of the 50 rod 28 carries a hand-wheel 34, by means of which it is rotated. When the hand-wheel 34 is rotated the post-member 1 will rotate, causing the nuts 18 and 19 to approach or 55 recede from each other, thereby altering the dimensions of the form at the waist and hip regions. The provision of the rod 28, and manner of connecting it to the member 1, makes it possible to positively alter the form at the hip and waist region from the top of the figure. 60 A further feature of the invention resides in the provision of the threaded post-member 2 which adjusts the length of the waist. By rotating the member 2 by means of the hand-wheel 7, it will move longitudinally of 65 the post member 1, carrying the threaded

sleeve 3 with it. In other words, the thrust produced by rotating the member 2 is imposed upon the sleeve 3, from there to the links 14, 14, and thence to the neck section. As the sleeve does not rotate during this operation, the form will separate or come together at the waist line according to the direction of rotation of the member 2. By providing the member 2 with a thread which engages a nut in the post member 1, the form 70 can be adjusted at the waist line without the use of springs. To lock the nut 19 against rotation, and consequently the nut 18, I provide the said nut 19 with a clamp 35, which surrounds the post member 1 and carries a 75 clamp-screw 36 (Fig. 8). When the clamp-screw 36 is screwed home, the form cannot be rotated without rotating the post-member 1; hence the hip dimensions cannot be 80 changed by inadvertently rotating the form. 85 When the clamp 35 is tightened the nut 19 and post member 1 will be locked together against independent rotation.

To reduce the cost of manufacture I prefer to make up the post-member 1 of two 90 parts clamped together, towit, a plain part 36^a and part 37 carrying right and left threads 16 and 17. To secure the parts together I employ a sleeve-clamp 38 (see Figs. 8 and 9). By this construction I am able to 95 take a section of tubing, of the proper length, thread it at both ends, right and left, and then clamp it to a plain section which does not require any threads; otherwise it 100 would be necessary to apply more threads than are usually required.

The brackets 21, consisting of an angle-member 39, provided with slots 40, and an adjustable frame 41 secured thereto by bolts and nuts 42, serve the purpose of permitting any inaccuracies in assemblage of parts 105 to be corrected. Should a non-adjustable bracket be secured to a section, out of alignment, it would throw the form out of plumb. By means of the combination bracket 21, I 110 can shift the frame one way or the other should the angle-piece 39 be applied out of place.

A further feature of my invention resides 115 in subdividing each portion of the form, that is, the shoulder, bust and hip regions into sections which are free to be adjusted independently of any adjustment of said portions by the adjustable supporting post. In Fig. 1, the shoulder sections are indicated 120 by 43, the bust sections by 44 and the hip sections by 45. Each shoulder section 43 is subdivided into sections 43^a and 43^b. Each bust section 44 is subdivided into sections 44^a and 44^b, and each hip section is subdivided 125 into sections 45^a and 45^b. Each shoulder section, as a whole, is connected to its adjacent bust-section by a toggle or universal connection 46 which permits the said shoulder sections to be moved outwardly or 130

upwardly, after releasing the binding screw 47 in the side plates 48, 48^a. To move the shoulder sections up or down the screws 47 will be loosened, but to move the shoulder sections outwardly they need not be loosened as the said slotted slidably connected plates 48 will yield. Each sub-section 43^a and 43^b of the shoulder sections are connected together by slotted plates 49, having in engagement therewith binding screws 50, each plate being pivotally secured at one end to the section 43^b, the section 43^a carrying the screw which passes through a slot 51 in the plate 49. Each shoulder section 43^b is likewise connected by a slotted plate 52 to the hip section 45^b, the plate being pivotally connected at one end to the hip section 45^b. The shoulder section 43^b carries a binding screw 53 which passes through the slot 54 in the plate 52. In addition to the toggle or universal connection 46 each shoulder section 43 is provided with a similar toggle or universal connection 55 connecting it to the adjacent bust section 44. Each toggle 46 and 55 is pivotally connected to a shoulder and bust section by binding screws 56 and 57 and to each other by binding screws 58. When the binding screws 56, 57 and 58 are released the shoulder sections can be moved away from the bust sections to broaden the shoulders, or moved vertically to raise the shoulders, after which the binding screws can be tightened thereby holding the parts in an adjusted position.

Should I desire to broaden or raise a shoulder without increasing the dimension of the form at the region indicated by F, or approximately the bust region, I would release the binding screws 50 and move the shoulder section upwardly as shown by dotted lines 59, Fig. 1. Should I desire to increase the dimension at the region F without changing the shoulder, as per dotted lines 60, Fig. 5, I would release the screws 50 and 53 and move the section 43^b outwardly, swinging the plates 49 and 52 upon their pivotal points. By this means I am able to change the contour of the form at the shoulder or at the bust line independently of any adjustment of the shoulder sections as a whole, or independently of each other. The combination of the universal connections 46 and 55 and the independently adjustable shoulder sections 43^a and 43^b makes it possible to alter the form at the points represented by these adjustable sections 43^a, 43^b to meet most any requirement. As the plates 49 and 52 are flexible they can be sprung outwardly, in line with the axis of their points of securement to their respective sections, to increase or alter the curvature of the bust, as shown by dotted line 61 (Fig. 3) independently of any adjustment obtained by manipulating the adjustable post D.

Each bust section 44^a, front and back, is connected to the bust section 44^b by flexible slotted plates 62, each plate 62 being pivotally connected at 63 to the bust section 44^b. The section 44^a carries a binding screw 64 passing through the slot 65. Each bust section 44^b is connected to a section 45^b by flexible slotted plates 66 pivoted at 67 to the hip section 45^b. A binding-screw 68, carried by the section 44^b, passes through the slot 69 in the plate 66. These sections can be adjusted independently of each other and also of any adjustment obtained by manipulating the post members in a manner described for the sections 43^a and 43^b.

An important feature of my invention resides in the multi-sectional hip section 45. Each section 45^a of the hip section is connected by slotted plates 70 to the adjacent hip section 45^b so that the section 45^a can be moved away from the hip section 45^b, as shown by dotted lines 71, Fig. 5. Each plate 70 is pivotally connected at 72 to the hip section 45^b. The hip section 45^a carries a binding screw 73 which passes through a slot 74 in the plate 70. Each hip section 45^a is likewise connected, at the top thereof, to the adjacent hip section 45^b by flexible slotted plates 75 pivotally connected at 76 to the hip section 45^b, a binding screw 77 on the section 45 passing through a slot in the plate 75.

The skirt portion C consists of a plurality of slotted bands 76 and vertical strips 77^a secured thereto, the band members being slidably connected together at 78. When the form is to be changed at the region G the band members 76 can be moved one upon the other to be adjusted in connection with the adjustment of the hip sections. The form can be adjusted at the hip region as indicated by dotted lines 78^a, Fig. 5, without changing the dimension at the region G.

The hip sections 45^a are located at the sides of the sections 45^b and constitute inserts or sub-divisions thereof which normally lie flush with the sections 45^b (Fig. 3). In other words, a part only of the hip sections 45 are rendered independently adjustable by the sub-divisions 45^a.

I am aware that it is not new to provide a garment form with a hip section or portion which is flexibly connected to the body section and composed of sub-sections connected laterally to each other by flexible devices permitting expansion, all of the said sub-sections being individually adjustable. This construction I do not claim, but

What I claim is:

1. In a garment form, a hip section consisting of relatively fixed and independently movable subdivisions, in combination with longitudinally slotted horizontal straps, each of which is pivoted to the lower part of one of said fixed subdivisions and connected

through its slot by an adjusting screw to the lower part of one of said movable subdivisions, and additional slotted straps, each of which is arranged obliquely downward 5 and outward and connected at its upper end to one of said relatively fixed subdivisions and connected through its slot by an adjusting screw to the upper part of one of said movable subdivisions for the purpose 10 set forth.

2. In a garment form, a hip-section consisting of relatively fixed subdivisions and independently movable subdivisions, in combination with a bust-section, connections between 15 said bust-section and said hip-section for adjusting the latter vertically, longitudinally slotted horizontal straps, each of which is pivoted to the lower part of one of said fixed subdivisions and connected through its slot by an adjusting screw to the lower part 20 of one of said movable subdivisions, and additional slotted straps, each of which is arranged obliquely downward and outward and connected at its upper end to one of said fixed subdivisions and connected through its slot by an adjusting screw to the upper part 25 of one of said movable subdivisions for the purpose set forth.

3. A garment-form comprising a plurality 30 of adjustable sections, means to adjust said sections, consisting of a supporting post comprising a plurality of threaded tubes one over the other, one of said tubes being provided with right and left hand threads, nuts 35 carried thereby, links connecting said nuts and the neck portion of said form, another tube being also provided with right and left hand threads and nuts carried thereby, links connecting said nuts and the hip portion of 40 said form, means located at the top of the form to rotate the first named threaded tube, means operable from the top of the form adapted to rotate the other tube, and a threaded tube to move said previously 45 named tubes away or toward each other to adjust the length of the waist portion of the form.

4. In combination with a garment-form having a hip portion and a bust portion 50 adapted for vertical adjustment relative to each other adjustable connecting devices between said hip portion and bust portion, a supporting post therefor consisting of a tubular member, a threaded nut carried 55 thereby, a threaded post engaging said nut, means carried by said threaded post connecting said post and the neck portion of the form, and means to rotate said threaded post whereby said bust and hip portions can 60 be adjusted relative to each other.

5. In combination with a sectional garment-form, an adjustable support consisting of a tube provided with right and left hand threads, a threaded nut carried thereby, a 65 hollow threaded post engaging the said nut,

means to rotate same, a plug carried by said tube provided with an angular opening, an angular rod passing loosely through said hollow post and slidably engaging said plug, means to rotate said rod, a thrust-collar carried by said rod and abutting the lower end of said threaded post, a sleeve surrounding said threaded post provided with right and left hand threads, and means to rotate said sleeve. 75

6. In combination with a sectional garment-form, an adjustable support consisting of a tubular member consisting of a plain section and a section provided with right and left hand threads, a clamp rigidly connecting said sections, a post adapted for movement longitudinally of the first named tubular section, and a sleeve carried by said post provided with right and left hand threads. 80

7. In combination with a sectional garment-form, an adjustable supporting post consisting of a tube provided with right and left hand threads, nuts carried by said threads and connected to the hip portion of the form, a hollow threaded post carried by said tube adapted for longitudinal movement therein, a sleeve carried by said post provided with right and left hand threads, nuts carried by said threads connected to the neck portion of the form, means to prevent longitudinal movement of said sleeve on said post, and means carried by said threaded post and slidably engaging said threaded tube adapted to rotate said threaded tube. 90

8. In combination with a sectional garment-form comprising a neck section, a bust section and a hip section a supporting post consisting of a tube provided with right and left hand threads, nuts carried by said threads and connected to the hip section of the form, a threaded post engaging said tube, means carried by said post connected to the neck portion of the form, and means to rotate said threaded tube upon the post in engagement therewith whereby the said bust section can be adjusted vertically. 105

9. In combination with a sectional garment-form, a supporting post consisting of a plurality of members adapted for movement longitudinally of each other, means carried by the lower member connecting said member with the hip portion of the form, means carried by the upper member connected to the neck portion of the form, and means carried by the upper member and slidably connected to the lower member whereby to rotate said lower member around the upper member. 110

10. In combination with a garment form, a supporting post therefor consisting of a fixed member provided with a plate at the upper end, a rotatable member, a flange carried by the rotatable member resting upon said plate, retaining lugs carried by said 115 120 125 130

plate and overlapping said flange, and means to lock said flange and plate together at will.

11. In combination with an extensible supporting post consisting of independently rotatable sections screwed together, the body of a garment form provided with two superposed series of sections or sub-divisions above the hip section thereof, and means connected to one of said post sections for operating some of the said sub-divisions to expand or contract some part of the upper portion of the form as desired.

12. In a garment-form, a hip-portion provided with movable inserted sections, which are connected near their lower ends by a pivot fixed in one of said sections to the adjacent sides of said hip-portion, in combination with a slotted plate and screw for adjusting the upper parts of said inserted sections outwardly from said sides, with the surface of which sides the said inserted sections are normally in contact.

13. In a garment form, a hip-portion provided with movable inserted sections, each of which sections is pivotally attached at both ends to the proximate hip-sections, in combination with means connected to the upper pivot of each section for permitting the adjustment of the upper end of said section outward and downward or inward and upward at will and means connected to the lower pivot of said section for permitting the adjustment of the latter horizontally inward and outward.

14. In a garment-form, a hip-portion provided with movable inserted sections, each of which is connected near its upper end to one of the sides of said hip-portion by an obliquely arranged longitudinally slotted

plate and clamping screw for adjusting said section outward and downward from said side, the lower part of said section being connected to said side by a longitudinally slotted plate and clamping screw and the latter plate being pivoted to said side as set forth.

15. In combination with a sectional garment-form, a supporting-post therefor, means carried by the post to adjust the sections of the garment-form, a supporting-bracket carried by each section provided with slots, a frame carried by each bracket, and provided with a slot positioned transversely of the slots in said brackets, securing bolts passing through said slots, and links connecting said frames and the adjusting means on said post.

16. In a garment-form, bust-sections and shoulder sections, each section consisting of an upper and a lower sub-section, in combination with toggle arms connecting each upper bust sub-section to the proximate upper shoulder sub-section and similarly connecting each lower bust sub-section to the proximate lower shoulder sub-section, slotted upright plates pivoted to the lower bust sub-sections and provided with clamping screws for adjusting said upper bust sub-section obliquely outward and upward as permitted by the yielding of the toggle arms, and similar plates pivoted to the lower part of the form and provided with screws for likewise adjusting the lower bust sub-sections.

Signed at New York city, N. Y., this 14 day of May 1914.

ISAAC LEVIN.
